Primary Examiner — Lauren D McVey*Assistant Examiner* — Elisa M Pujals*(74) Attorney, Agent, or Firm* — George D. Morgan(57) **CLAIM**

The ornamental design for a toy car, as shown and described.

DESCRIPTION

FIG. 1 is a front perspective view of a toy car, showing my new design;
 FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and,
 FIG. 10 is an enlarged detail view of area 10 in FIG. 2.

The evenly spaced broken lines depict portions of the article that form no part of the claimed design. The dash-dot-dash broken lines depict bounds of the enlarged views. The broken lines form no part of the claimed design.

1 Claim, 10 Drawing Sheets(56)
